UNITED STATES PATENT OFFICE.

LOUIS H. BUEK, OF PHILADELPHIA, PENNSYLVANIA, ASSIGNOR, BY MESNE ASSIGNMENTS, TO UNITED SHOE MACHINERY CORPORATION, OF PATERSON, NEW JERSEY, A CORPORATION OF NEW JERSEY.

SHOEMAKING.

1,365,765.

Specification of Letters Patent. Patented Jan. 18, 1921.

Application filed April 14, 1917. Serial No. 162,023.

To all whom it may concern:

Be it known that I, LOUIS H. BUEK, a citizen of the United States, residing at Philadelphia, in the county of Philadelphia and State of Pennsylvania, have invented 5 certain Improvements in Shoemaking, of which the following description, in connection with the accompanying drawings, is a specification, like reference characters on 10 the drawings indicating like parts in the several figures.

This invention relates to improvements in the manufacture of boots and shoes and more particularly to methods of forming 15 lasted heel seats.

In one of its aspects the invention consists in preliminarily molding the lasted heel seat of a boot or shoe while in temper into shape to fit the upper surface of a heel, 20 particularly around its margin. It will be understood that in lasting the heel seat of a welt shoe the overdrawn portions of the upper and lining lie more or less unevenly on the surface of the insole and the lip of 25 the insole, which is raised in the welt sewing operation, stands off from the body of the insole. Heretofore it has been the practice to beat down the heel seat to shape it for the reception of the outsole. I have discovered, 30 however, that this lasted heel seat may be shaped by a molding operation so that the heel may be attached directly thereto.

In carrying out my improved method the lasted heel seat is molded while the shoe is 35 in temper from the lasting operation so as to form a U-shaped surface lying in a single plane about a central convex portion. Subsequently a heel is attached with its margin fitted upon the U-shaped surface so formed. 40 In this way a very close union is formed between the shoe and the heel, the opening of the rand crease being substantially eliminated. This not only improves the appearance and finish of the shoe but facilitates 45 the attaching operation by providing a firm bearing for the heel and removing soft areas from the heel seat.

In subjecting the heel seat to molding pressure, the upstanding lip of the insole 50 is molded down into substantially its original position as a part of the insole. This step is advantageous in that it tends to produce a solid and compact heel seat. It is believed that the molding of an upstanding

insole lip back into its original position has 55 not been heretofore attempted for any purpose in shoemaking.

In some cases it has been found desirable to supplement the molding operation performed on the heel seat by working the 60 upper and the counter of the shoe toward the heel seat so as to form a more abrupt shoulder about the margin of the heel seat. This tends to close the rand crease still further by increasing the fullness of the upper 65 where it comes into contact with the heel.

The method of my invention may be carried out before or after the insertion of a shank piece in the shoe. If the shank piece has been inserted prior to the molding operation 70 a transverse shoulder is formed in the shank piece and the breast edge of the heel is fitted into this shoulder when the heel is attached. If the shank piece has not been inserted at the time of the molding operation 75 a transverse shoulder is formed in the material of the inseam at each side of the shoe.

If desired the heel seat may be provided with a covering piece of leather or leather-board 80 so located as to close the opening between the edges of the overdrawn upper. This covering piece, when used, is molded into convex form and may be a part of the molded heel seat.

These and other features of the invention will be best understood and appreciated from the following description of a preferred embodiment thereof selected for purposes of illustration and shown in the accompanying drawings, in which—

Figure 1 is a view in perspective of the heel seat portion of a lasted shoe;

Fig. 2 is a similar view showing the shoe provided with a shank piece and a heel seat 95 covering piece in condition after the molding operation;

Fig. 3 is a similar view showing a heel in place upon the heel seat, a portion being broken out to show the cross sectional configuration;

Fig. 4 is a view in side elevation of the apparatus showing the shoe in process, and

Fig. 5 is a fragmentary view illustrating the effect of the molding operation upon the 105 insole lip.

As shown in Fig. 1, the lasted portion of a welt shoe comprises the outer or leather part

10 and the lining part 12 the margins of which are drawn inwardly over the insole 14 and secured in place by lasting tacks. The welt 16 terminates at either side of the 5 shank adjacent to the point where the breast of the heel is to be located. The welt is stitched to the outer and lining parts of the upper and also through the inseam lip 18 which is raised appreciably from the body of 10 the insole prior to or during the welting operation. The condition of the heel seat prior to its treatment in accordance with my invention is shown in Fig. 1.

It is entirely practical and within the 15 scope of the invention to subject the lasted heel seat in the condition shown in Fig. 1 directly to the molding operation but in some cases it has been found desirable, as indicated in Fig. 2, to insert a shank piece 20 20 in its usual position between the material of the inseam at the shank of the shoe and to attach a covering piece 22 to the heel seat portion before carrying out the molding operation. The covering piece 22 comprises 25 a piece of suitably shaped material of such size as to cover the margins of the over-drawn upper material and the rear end of the shank piece 20.

Having prepared the heel seat as above 30 outlined a molding die of proper shape is forced against the heel seat while the latter is still in temper from the lasting operation and the U-shaped surface 24 is formed about the margin of the heel seat. Within the U- 35 shaped surface the central portion of the heel seat is molded into convex form similar in shape to the concave heel seat surface of the heel to be attached. At the same time a transverse shoulder 26 is molded in 40 the rear end of the shank piece 20 and the material of the inseam at either side of the shank. Against this transverse shoulder 26 the breast edge of the heel is intended to be fitted.

45 In the molding operation above outlined the inseam lip, which at this stage of the manufacture of the shoe stands at an angle to the insole, is molded downwardly into substantially its original position as a part 50 of the insole.

During the molding operation, if desired, the material of the counter portion of the shoe may be worked toward the heel seat so as to form a more abrupt shoulder at the 55 margin of the heel seat and shift the fullness of the counter toward the rand crease. As already explained this tends to close the rand crease and make a very close union between the heel and the upper. As indicated in Fig. 4 this operation may be effected by oblique blows of a hammer 28.

Having prepared the heel seat in the manner above outlined the heel is glued or cemented in place with its margin fitting 60 against the U-shaped surface 24 and its

breast edge fitting against the transverse shoulder 26. It will be seen that since the U-shaped surface 24 lies in a single plane it will bear fairly against the entire periphery of the heel seat surface of the heel 70 and the opening of the rand crease will thus be reduced to a minimum. The cemented heel is allowed to remain under pressure until the cement is thoroughly dried and subsequently the union between the heel and 75 the shoe is reinforced by attaching nails driven from inside the shoe. Preliminarily to attaching the heel the outsole 30 is stitched to the welt. The rear portion of the outsole is reduced in thickness to form 80 a flap 32 which is subsequently turned up and secured to the breast face of the heel.

The method above outlined may be carried out with the aid of any suitable apparatus, one step being illustrated in Fig. 4. 85 As shown in this figure a frame 40 is provided with a horizontal surface to support a last stand 42 having a pin for entering the pin hole of the last 44 and thus supporting the heel seat portion of a lasted shoe. 90 A bolt 45 passing loosely through a hole, located eccentrically in the base of the stand, connects the stand to the frame and serves as a fulcrum about which the stand with the shoe thereon may be moved into and 95 out of operative position.

The frame has a transverse arm or bar extending from its upright portion and provided at its outer end with a threaded vertical bore for a screw spindle 46. At its 100 upper end the spindle 46 is provided with a hand wheel 48 by which the spindle may be forced downwardly against the shoe to create the molding pressure. At its lower end the screw spindle 46 is connected 105 through a universal joint to a foot plate 48. The foot plate 48 is adapted to bear upon the upper surface of the mold 50 which is placed upon the heel seat of the shoe, the universal joint permitting the foot plate to 110 accommodate itself to the angle of the mold. The mold itself comprises a block shaped to cover a predetermined area of the heel seat and having a concave lower surface surrounded by a marginal rib shaped for molding 115 the U-shaped flat surface of the heel seat.

In using the apparatus above described, the shoe is jacked and the mold forced into operative position. While the heel seat is 120 thus subjected to molding pressure and the lasted shoe held rigidly the operation of drawing the material of the counter upwardly toward the mold is carried out by blows of the hammer 28.

While the invention has been described in connection with the molding of the heel seat of a welt shoe, it is apparent that it would be within the scope of the invention to apply it to the manufacture of turn shoes. 130

Having thus described my invention, what I claim as new and desire to secure by Letters Patent of the United States is:

1. In the manufacture of boots and shoes, that method which comprises, molding the lasted heel seat portion of a welt shoe to form a flat U-shaped surface and a transverse shoulder in the material of the inseam at each side of the shank and then attaching a heel with its breast edge lying against said transverse shoulder.
2. In the manufacture of boots and shoes, that method which comprises, molding the lasted heel seat of a welt shoe to close down the upstanding insole lip, and then completing the bottoming operations.
3. In the manufacture of boots and shoes, that method which comprises, molding the lasted heel seat of a welt shoe to close the lip of the insole and form a flat U-shaped surface about the margin of the heel seat, and then attaching a heel to the heel seat so formed.
4. In the manufacture of boots and shoes, that method which comprises, securing a thin covering piece to the lasted heel seat, molding the covering piece in convex form and molding the portion of the heel seat
- without the covering piece to form a flat surface, and attaching a heel with its margin fitting upon the flat surface.
5. In the manufacture of boots and shoes, that method which comprises, securing a shank piece to the bottom of a lasted shoe, securing a covering piece to the heel seat overlapping the rear end of the shank, molding the covering piece in convex form, simultaneously molding a transverse shoulder across the shank, and attaching a heel with its breast edge fitting against the transverse shoulder.
6. In the manufacture of boots and shoes, that method which comprises molding the upstanding insole lip of a lasted welt shoe down into its original position as a part of the insole.
7. The method of manufacturing shoes which comprises convexly molding the heel seat of a shoe to which the outsole has not yet been attached to fit the concave heel seat of a heel, and then attaching a heel to the heel seat thus molded and a sole to the forward and shank portions of the shoe.

In testimony whereof I have signed my name to this specification.

LOUIS H. BUEK.
